Specification for Design.

Patented Apr. 9, 1912.

Application filed March 17, 1911. Serial No. 615,119. Term of patent 14 years.

To all whom it may concern:

Be it known that I, CHARLES EDWARD HAVILAND, a citizen of the United States, residing at Limoges, France, have invented a new, original, and ornamental Design for a Handle for a Dish or Bowl or Similar Article of Tableware, of which the following is a specification, reference being had to the accompanying drawings, forming part thereof, and in which—

Figure 1 is a perspective view; Fig. 2 a side elevation; Fig. 3 an end elevation, and

Fig. 4 a top view of a handle for a dish or bowl or similar article of tableware embodying my design.

I claim:

The ornamental design for a handle for a dish or bowl or similar article of tableware, as shown.

CHARLES EDWARD HAVILAND.
